UNITED STATES PATENT OFFICE.

GEORGE WATKINSON, OF NEW HAVEN, CONNECTICUT.

PANTS-PROTECTOR.

SPECIFICATION forming part of Letters Patent No. 281,213, dated July 10, 1883.

Application filed December 4, 1882. (No model.)

To all whom it may concern:

Be it known that I, GEORGE WATKINSON, of New Haven, in the county of New Haven, in the State of Connecticut, have invented new 5 and useful Improvements in Pants-Protectors, of which the following, taken in connection with the accompanying drawings, is a full, clear, and exact description.

This invention relates to that class of pants- 10 protectors in which a tongue is adjustably attached to a plate adapted to be secured to the heel of a boot or shoe of either rubber or leather.

My invention consists in an improved construction and combination of the constituent 15 parts of the pants-protector, whereby the cost of the manufacture of same is reduced and the operation of the device is rendered more efficient and durable, all as hereinafter more 20 fully described.

In the accompanying drawings, Figure 1 is a rear view of the heel of a rubber shoe provided with my improved pants-protector, the latter being shown in the position in which it is 25 placed when not required for use for the purpose of better illustrating the construction of the device. Fig. 2 is a side view of the same; Fig. 3, a vertical section with the pants-protector in its operative position shown by dotted lines; and Fig. 4 is a detached view of the 30 plate by which the pants-supporting tongue is secured to the heel of a boot or shoe.

Like letters of reference denote like parts in all the figures.

35 *a* is a metallic plate adapted to be secured to the heel of a boot or shoe either of rubber or leather. When to be attached to rubber, I prefer to provide it with vertical slots *b b*, for the reception of clinching-spurs *r*, which 40 project from a washer, *w*, applied to the inner side of the rubber, and pass through the rubber and aforesaid slots, and are bent down upon the outside of the plate *a*, as shown in Fig. 1 of the drawings. When the plate *a* is 45 to be applied to the heel of a leather boot or shoe, I prefer to employ screws passing through suitable holes in the said plate and into the solid leather of the heel. The plate *a* is provided with ears *e e*, on which is 50 hinged a tongue, *d*, the hinged end of which is formed with a V-shaped cam or angular enlargement, *c*, between the ears *e e*. Under the cam *c* lies a spring-plate, *s*, which projects from the plate *a* and presses against the aforesaid cam, so that by its bearing on the rear

or flat sides of the cam it yieldingly holds the tongue both in its elevated position, as shown in Figs. 1 and 2 of the drawings, and in its rearward projecting position, as indicated by dotted lines in Fig. 3 of the drawings, the former position being that in which the tongue is placed when not required for use, and the latter position being its operative position. The pressure of the projecting portion of the cam *c* against the spring *s* automatically throws 65 the tongue into its aforesaid position, and, while allowing said tongue to yield to an accidental straining below its projecting or operative position, it causes the same to spring back into its said requisite position as soon as it 70 is released from the said undue strain. The danger of breaking the device as well as of tripping the wearer of the boot or shoe to which my improved pants-protector is applied is thus effectually obviated.

In order to reduce the cost of the manufacture of the described pants-protector, and also to render the same more durable, I make the spring *s* integral with the plate *a* by making in the upper end of said plate two vertical slots, 80 *n n*, between the ears *e e*, the free end of the intermediate portion of the plate forming the spring *s*. The base of the plate *a* I form with a rigid rearward projection, *u*, upon which to apply the pressure of the toe of one foot in 85 drawing off the shoe from the other foot.

Having described my invention, what I claim as new, and desire to secure by Letters Patent, is—

A device for protecting the bottoms of pants, 90 consisting of the plate *a*, adapted to be secured to the heel of a boot or shoe, and provided at its upper edge with the ears *e e*, and an intermediate spring, *s*, formed by slots *n n*, in combination with a hinged tongue, *d*, having a cam, *c*, and adapted to be turned either 95 out at right angles to the plate or into a plane with the plate, all constructed and combined substantially in the manner described and shown, for the purpose set forth.

In testimony whereof I have hereunto signed my name and affixed my seal, in the presence of two attesting witnesses, at Syracuse, in the county of Onondaga, in the State of New York, this 24th day of November, 1882.

GEORGE WATKINSON. [L. S.]
